UNITED STATES PATENT OFFICE.

WILLIAM HYDEN, OF KINGSTON, WEST VIRGINIA.

TRUCK.

1,337,914.

Specification of Letters Patent. Patented Apr. 20, 1920.

Application filed August 12, 1918. Serial No. 318,454.

To all whom it may concern:

Be it known that I, WILLIAM HYDEN, a citizen of the United States, residing at Kingston, in the county of Fayette and State 5 of West Virginia, have invented new and useful Improvements in Trucks, of which the following is a specification.

This invention relates to trucks for mining machines and the principal object of the 10 invention is to provide a truck which will permit the mining machine to be rotated thereon so as to permit the cutters to work from any desired direction.

Another object of the invention is to provide means for adjusting the cutting machine after each cut so that the cuts will 15 connect with each other.

Still another object of the invention is to provide means for holding the truck stationary 20 when the cutting machine is being operated.

The invention also consists in certain other features of construction and in the combination and arrangement of the several 25 parts, to be hereinafter fully described, illustrated in the accompanying drawings and specifically pointed out in the appended claim.

In describing my invention in detail reference will be had to the accompanying drawings wherein like characters denote like or corresponding parts throughout the 30 several views, and in which:—

Figure 1 is a plan view of my truck with the mining machine removed;

Fig. 2 is a side view of the truck with the mining machine thereon;

Fig. 3 is a plan view showing the mining machine located at right angles to the 40 truck;

Fig. 4 is an end view of the truck and machine as shown in Fig. 3;

Fig. 5 is a sectional detail.

In these views 1 indicates a truck which 45 consists of the side beams 2, the heavy rounded end pieces 3 and the braces 4 which are located between the side pieces. The truck is mounted upon the shafts 5 which carry the wheels 6. Centrally arranged on 50 the truck is a ring-shaped member 7. This member is provided with the holes 8 which are spaced apart as shown, and the inner circumference of said member is provided with a rack 9. A cross piece 10 is arranged 55 in the center of the truck with its top face

flush with the top face of the ring-shaped member and this cross piece is provided with an opening 11 which is adapted to receive a king bolt 12 for securing the mining machine, indicated generally at A, to the truck. 60 This mining machine may be of any desired type and will not be described in detail. The lower portion of the machine is provided with the gears 13 for meshing with the rack. 65

It will thus be seen that the mining machine may be rotated upon the truck, the machine turning about the king bolt and guided by the ring-shaped member. I provide pegs 14 which engage the holes 8 in 70 the ring-shaped member to hold the machine in adjusted position. The holes are so positioned that each cut made by the machine will connect with the previous cut.

One of the cross pieces 3 carries a pointed 75 member 15 for engaging the shaft head to hold the truck against movement while the cutting machine is being operated. The other cross piece is provided with the coupler means 16 for coupling the truck to 80 the motor. When so coupled the motor helps to hold the truck stationary. If desired, however, the truck may be chained to the rails of a track.

It is thought from the foregoing description that the advantages and novel features 85 of my invention will be readily apparent.

I desire it to be understood that I may make changes in the construction and in the combination and arrangement of the several 90 parts, provided that such changes fall within the scope of the appended claim.

What I claim is:—

A truck of the class described comprising side and end pieces, a centrally located cross 95 piece having an opening therein for receiving the king bolt, wheels carried by the truck, a ring shaped member centrally arranged on the truck and having a rack formed on its inner periphery, a cutting 100 machine carried by the truck and rotatably held thereon by the king bolt, a gear carried by the machine and engaging the rack and means for locking the cutting machine to spaced parts of the ring member so that 105 each cut made by the machine will connect with the previous cut.

In testimony whereof I affix my signature.

WILLIAM HYDEN.
